UNITED STATES PATENT OFFICE.

JULIUS H. GILLIS, OF ANACONDA, MONTANA, ASSIGNOR TO ANACONDA COPPER MINING COMPANY, OF ANACONDA, MONTANA, A CORPORATION OF MONTANA.

CONDUCTOR-BAR.

1,276,208.

Specification of Letters Patent. Patented Aug. 20, 1918.

Application filed August 6, 1917. Serial No. 184,705.

To all whom it may concern:

Be it known that I, JULIUS HOWELLS GILLIS, a citizen of the United States, residing at Anaconda, in the county of Deerlodge 5 and State of Montana, have invented certain new and useful Improvements in Conductor-Bars, of which the following is a specification.

The present invention relates to conductor bars for use in the electrolytic process for depositing metals or other substances by electricity, and more particularly to conductor bars for carrying electric current to cells having a large number of electrodes in multiple.

It is the special object of my invention to construct conductor bars in such a way as to effect the saving of a considerable amount of material from which conductor bars are usually made, reduce the difficulty of cleaning the contact surfaces to a minimum and facilitate the supervision.

To carry out the object of my invention in what I consider the preferred form, I propose to decrease the cross-section of the conductor bars from one portion to another in the same ratio as the current flowing through the bars decreases, to reduce the contact area to a minimum, and to shape the bars so that they can be conveniently situated at the same side of the cells, preferably adjacent the working aisles.

For a fuller understanding of my invention, I refer to the appended drawings, in which—

Figure 1 is a plan view of a preferred form of conductor bar;

Fig. 2 is a side elevation thereof;

Fig. 3, a section on line 3—3 looking in the direction of the arrows;

Fig. 4 a section on line 4—4 looking in the direction of the arrows;

Fig. 5 a sectional view through a double row of cells, each having the conductor bars belonging to it located at one side;

Figs. 6, 7 and 8 are diagrammatic views of various connections, Fig. 6 showing the arrangement of the cells and bars in Fig. 5, Fig. 7 connections for a single row of cells, 50 and Fig. 8 a modification of the arrangement of Fig. 5.

Figs. 1 and 2 represent a preferred type of conductor bar 1 interconnecting electrodes of opposite sign of two cells. The

length of the bar is therefore substantially 55 equal to the combined length of two adjacent cells. Since the current flowing through the bar increases from the extreme end toward the center and decreases again from the center toward the other end, I have 60 increased the cross-sectional area of the conductor bar from the ends toward the center and dimensioned the bar, as is well understood, so that the bar may conduct the current without any undue loss. 2 and 3 are 65 ribs on opposite sides of the center of the bar 1, rib 2 extending along the inner edge and rib 3 along the outer edge of the bar. These edges are substantially parallel to the median longitudinal line of the bar. 70 From the center, the bars are cut substantially diagonally so that the bar has the form of two equal rectangular triangles, base to base, but the hypotenuse being located at opposite sides. At the center there 75 is an offset 4 by which one-half of the bar is raised above the other half. This feature is not a part of the invention, but is merely incident to a general arrangement of the cells in which successive cells are placed on 80 successively higher levels and the offset is equal to the difference between the respective levels.

When the various bars are in alinement as shown in Fig. 6, the rib 2 of one bar and rib 3 of the adjacent bar run parallel with each other the length of one cell. Then rib 2 which together with rib 3 just mentioned forms a single bar runs parallel to rib 3 of the next bar the length of the next cell, and 90 so on.

The ribs 2 and 3 which provide flat contact surfaces 5 and 6, respectively, for supporting the electrodes are of different heights. Ribs 3, which are higher than ribs 95 2, are located on the outside relatively to the cells and ribs 2 on the inside directly adjacent the cells, so that the connector bars 7 on the electrodes of one sign clear ribs 2 and rest on ribs 3, while the connector bars 100 8 on the electrodes of opposite sign rest on ribs 2. The difference in the height of the ribs is a matter of judgment and may of course be varied to suit particular requirements. The upper flat surfaces 5 and 6 are 105 so dimensioned that the area of contact between the ribs and any of the connector bars 7 and 8 is sufficient to carry the current

without undue heating. To insure good contact it is only necessary to keep these surfaces 5 and 6 clean, and since these surfaces are comparatively small and raised from 5 the body of the conductor bar, it is very easy to clean them and keep them in good condition.

Fig. 5 shows an arrangement of the conductor bars, such as indicated diagrammatically in Fig. 6. The set is formed of a double row of cells and the conductor bars belonging to one row are disposed at one side of that row and the conductor bars of the second row are placed at one side of that 15 row and the disposition is such that the two sets of conductor bars run along the outer side of the two rows and are thus readily accessible for inspection. In this figure, 9 and 10 are adjacent cells in the two rows. 20 11, 12, 13 and 14 are the walls of the two cells, respectively. The conductor bars are mounted on walls 11 and 14 and insulated therefrom by insulating layers 15 and 16. Suitable means, such as angle rails 17, 18, 25 19 and 20, may be employed to laterally support the conductor bars.

Along the top of walls 12 and 13 extend bars 21 and 22 of insulating material, such as wood or other suitable material and 30 these bars are of such height that they are flush with the ribs 2. The connector bars 8 (not shown in this figure) bridge the cell and are supported on the one side on rib 2 making electrical contact therewith, and 35 rest on the other side on bars or beams 21 and 22, respectively.

Connector bars 7 are supported on the one side on ribs 3 making electrical contact therewith and rest on the other side on bars 40 21 and 22, respectively. Fillers 23 and 24 are interposed between connector bars 7 and bars 21 and 22 to compensate for the difference in the height of ribs 2 and 3.

The cells may be advantageously covered 45 to keep out the dust and foreign matter. 25 and 26 represent covers pivoted on hinges 27 and 28. The hinges are fastened to a beam 29 supported on beams 30 and 31, and frames 32 and 33 extend around the 50 top of the cells below the free edge of the covers and above the conductor bars and connector bars for the covers to rest on and to form a closure.

In Fig. 7 is shown a single row of cells 55 and a modified form of conductor bars located at both sides of the cells. The conductor bar 50 has a single rib 51 along the inner straight edge 52 interconnecting all anodes of one cell and all cathodes of the 60 next cell.

Fig. 8 shows a similar conductor bar applied to two rows of cells in which each pair of adjacent cells is connected in series. Between the cells of each pair is placed a conductor 55 of uniform cross-section. Con-

ductor bar 56 interconnects all the anodes of cell 57, the cathodes of cell 57 and anodes of cell 58 are connected to conductor bar 55 and the cathodes of cell 58 to conductor bar 59.

Figs. 6, 7 and 8 are merely intended to illustrate some of the ways in which the invention can be applied.

While my invention is principally intended for use in connection with electrolytic cells, it is equally applicable to all other uses in which current is collected by a common conductor from a plurality of frequently detached electrical devices removably connected to the conductor.

I claim:

1. A conductor bar having a uniformly varying cross-section, and rib portions along its surface having flat contact areas.

2. A conductor bar having a uniformly varying cross-section, and rib portions along its surface having flat and uniform contact areas.

3. A conductor bar having a uniformly varying cross-section, and a contact rib along its surface.

4. A conductor bar having a uniformly variable cross-section, and a contact rib along its surface of uniform cross-section.

5. A conductor bar having a uniformly varying cross-section, and a straight contact rib of uniform cross-section along its surface.

6. A conductor bar having a uniformly varying rectangular cross-section, and a contact rib of a uniform angular cross-section along its surface.

7. A conductor bar having the shape of a wedge, and a contacting rib along one edge thereof.

8. A conductor bar having the shape of two wedges placed base to base.

9. A conductor bar having the shape of a double wedge placed base to base, and rib portions along its surface.

10. A conductor bar having the shape of a double wedge placed base to base, and rib portions of uniform cross-section along its surface.

11. A tapered conductor bar, and rib portions thereon having flat and uniform contact areas.

12. A conductor bar having substantially the form of an elongated rhombohedron.

13. A conductor bar having substantially the form of an elongated rhombohedron, and contacting ribs on opposing sides.

14. A conductor bar having substantially the form of an elongated rhombohedron, and rib portions having flat and uniform contacting areas, said rib portions being disposed on opposing sides of the rhombohedron.

15. A conductor bar having substantially the form of an elongated rhombohedron,

- and ribs presenting flat and uniform contact surfaces, said ribs being disposed along opposing edges of the rhombohedron.
16. The combination with an electrolytic cell of two conductor bars of uniformly varying cross-section disposed at one side of the cell in such a manner that the cross-sectional area of the two bars is substantially the same as the largest cross-sectional area 10 of one bar.
17. The combination with an electrolytic cell of two conductor bars disposed adjacent each other at one side of the cell and contacting ribs on each of the conductor bars.
- 15 18. The combination with an electrolytic cell of two conductor bars disposed adjacent each other at one side of the cell and contacting ribs of different heights one on each of the conductor bars.
- 20 19. The combination with an electrolytic cell of two conductor bars disposed at one side of the cell and each of uniformly varying cross-section and contacting ribs on each of the said conductor bars.
- 25 20. The combination with an electrolytic cell of two conductor bars disposed at one side of the cell, each of uniformly but oppositely varying cross-section.
21. The combination with an electrolytic cell of two conductor bars of uniformly but oppositely varying cross-section disposed at one side of the cell in such a manner that one edge of one bar runs parallel to one edge of the other bar. 30
22. The combination with an electrolytic cell of two conductor bars of uniformly but oppositely varying cross-section disposed at one side of the cell in such a manner that one edge of one bar runs parallel to one edge of the other bar, and a contacting rib on each 35 of said parallel edges.
23. The combination with an electrolytic cell of two conductor bars of uniformly but oppositely varying cross-section disposed at one side of the cell in such a manner that one edge of one bar runs parallel to one edge of the other bar, and a contacting rib on each of said parallel edges, one rib higher 40 than the other.
24. The combination with a plurality of 50 cells forming a row of a plurality of conductor bars of uniformly varying cross-section disposed in pairs at one side of the row.

In testimony whereof I affix my signature.

JULIUS H. GILLIS.
